UNITED STATES PATENT OFFICE.

THEODORE F. HUSSA, OF MONTCLAIR, NEW JERSEY.

METHOD OR ART OF SINGEING THREADS.

1,374,376.

Specification of Letters Patent. Patented Apr. 12, 1921.

Application filed January 15, 1918. Serial No. 211,918.

To all whom it may concern:

Be it known that I, THEODORE F. HUSSA, a citizen of the United States, residing at Montclair, in the county of Essex and State 5 of New Jersey, have invented certain new and useful Improvements in Methods or Art of Singeing Threads, of which the following is a specification, reference being had therein to the accompanying drawings, which form 10 a part thereof.

My invention relates to a method or art of singeing threads and more particularly to such a method or art, the practice of which involves the use of an electrical resistance 15 element.

Heretofore in this art, it has been the practice to pass thread to be singed through an incandescent troughed element in such close juxtaposition thereto as will permit the flame 20 from the element to impinge upon the thread and thus remove the fluff therefrom. If the thread be passed horizontally through the trough, the residue removed by singeing, will fall upon the element and rapidly foul the 25 same in a manner to interfere with the development of an effective flame therefrom. To avoid this difficulty it has been the practice to arrange the trough vertically, so that the incinerated particles will tend, under 30 gravity, to fall away from the trough. It has been proposed in connection with singeing apparatus of this general character, to utilize an air jet directed axially of the trough for removing the incinerated particles, and promoting combustion about the 35 element, but I have found in actual practice that the use of such a jet has a sufficient cooling effect upon the element, to extinguish the flame, or prevent the element reaching a 40 state of incandescence.

With these conditions in mind, it has been my effort to evolve a method or art which in addition to preventing the accumulation of incinerated particles of fluff upon the incandescent singeing element, will promote combustion about the said element, thus insuring substantial uniformity in the flame volume throughout the entire length thereof, and direct the flame in a manner to insure a more thorough singeing of the thread and permit a more rapid rate of traverse thereof in relation to said singeing element.

The invention consists in a method or art of singeing threads consisting in the novel 55 steps and practices hereinafter set forth and

described and more particularly pointed out in the claims hereto appended.

Referring to the drawings:

Figure 1 is a front elevation of a portion of an apparatus used in the practice of the 60 method or art of my invention; and

Fig. 2 is a vertical section therethrough.

Like letters refer to like parts in both of said views.

In the practice of the method or art of my 65 invention, I utilize a troughed singeing element, indicated at *a* in the accompanying drawings, through which trough the thread *b* to be singed is passed axially thereof. The trough *a* is so positioned as to extend substantially vertically. The singeing element *a* is made incandescent by an electrical current derived from the bus-bars *c* and *d* in electrical connection with opposite terminals of said element. As the said thread *b* passes 70 within and in close juxtaposition to the troughed element *a* the flame from this element will incinerate the fluff thereon, the thread subsequently being passed over a drum and rewound in the usual manner preparatory to its subsequent use. To prevent the accumulation of incinerated particles upon the element *a*, and at the same time facilitate the bringing of the element to a high degree of incandescence, I introduce a 75 gentle circulation of air about the element, the general direction of the flow of the air being axially thereof. The manner of introducing the air about the element must be such as not to impinge upon the element, as 80 I have found in practice that the impingement of the air in the form of a jet upon the element has the effect of extinguishing the flame and hence of preventing its action upon the thread to remove the fluff therefrom. To prevent this condition developing in the practice or art of my invention, I use a suction device which will have the effect 85 merely of causing a flow of air at a low rate of speed, the air being admitted in sufficient 90 volume about all sides of the element to avoid the formation of a jet, and cause it to flow about the element without impinging directly thereon in jet form. By directing the air as it enters the current flowing about 95 the element, across the edges of the trough, the flame emanating from said trough, is caused to more or less encircle the thread thus insuring the complete incineration of the fluff at all points about said thread. By 100

110

introducing the air upon opposite sides of the element as well as at one end thereof, a slight whirling of the air is secured, which as stated, has a tendency to cause the flame 5 to completely envelop the thread.

In the practice of my method or art, it is essential that the resistance element be arranged with the trough thereon extending vertically, and it is preferable to have the 10 current of air run counter to the natural draft, or downwardly, so that this current of air may assist gravity in carrying away the incinerated fluff.

The direction and control of the air about 15 the element a is secured by the arched plate e which incloses said element and extends adjacent the base a' thereof carrying said element, sufficient space being afforded between the edges of said plate and said base 20 to permit air to flow freely within said plate. The curvature of the inner wall of said plate will direct the air above the trough, the slow rate of flow of the air axially of said plate and said trough developing the whirling effect above referred 25 to. The means for creating and maintaining the desired circulation of the air with its low rate of flow, may consist of an ordinary fan, as shown, or of any other desired mechanism. 30

The method or art of my invention briefly summarized consists in passing a thread axially, through a vertically extending troughed element, creating sub-atmospheric 35 pressure adjacent that end of the element at which the thread passes from the element after being singed, admitting air both adjacent that end of the element where the thread enters the trough, and upon opposite 40 sides of the element, and directing the incoming air in a manner to impart a slight whirling action to the gentle current of air thus induced so as to cause the flame, to more or less completely envelop the thread. 45 By causing this current of air to run counter to the natural draft, there is a tendency toward an equalization of the volume of the flame throughout the entire length of the element, and by maintaining a low rate of 50 flow of the air any tendency toward extinguishment of the flame is avoided. The constant movement of air, will prevent the incinerated particles of fluff, accumulating upon, and remove them from adjacent, the 55 element, so as to insure continuity in the singeing operation under uniform flame conditions.

The method or art of my invention is not limited to the use of an apparatus having

the structural characteristics shown in the 60 accompanying drawings, it being apparent that the desired effect may be secured in a variety of different ways.

Having described the invention what I claim as new and desire to secure by Letters 65 Patent is:—

1. The herein described method or art of singeing threads consisting in passing a thread in close juxtaposition to a vertically extending incandescent, electrical resistance 70 member while causing an induced current of air having a low rate of flow to pass axially of, and transversely about, said resistance member.

2. The herein described method or art of 75 singeing threads consisting in passing a thread in close juxtaposition to a vertically extending incandescent, electrical resistance member while causing an induced current of air having a low rate of flow to pass axially 80 of, and transversely about, said resistance member, limiting the admission of air about said member to one end and upon opposite sides for substantially the full length 85 thereof, and controlling the flow of the incoming air to cause the flame from said element to substantially envelop the thread.

3. The herein described method or art of singeing threads consisting in passing a 90 thread in close juxtaposition to a vertically extending incandescent, electrical resistance member while causing an induced current of air having a low rate of flow to pass axially of, and transversely about, said resistance member, in a direction counter to the natural 95 draft about said member.

4. The herein described method or art of singeing threads consisting in passing a 100 thread in close juxtaposition to a vertically extending incandescent, electrical resistance member while causing an induced current of air having a low rate of flow to pass axially of, and transversely about, said resistance member, in a direction counter to the natural 105 draft about said member, limiting the admission of air about said member to one end and upon opposite sides for substantially the full length thereof, and controlling the flow of the incoming air to cause the flame from said element to substantially envelop 110 the thread.

In witness whereof, I hereunto affix my signature in the presence of two subscribing witnesses, this 19th day of December 1917.

THEODORE F. HUSSA.
